UNITED STATES PATENT OFFICE.

HENRY J. HALVERSON AND WILLIAM HAROLD YOUNGSTROM, OF CHICAGO, ILLINOIS, ASSIGNORS TO NEW BUSINESS CORPORATION, OF CHICAGO, ILLINOIS, A CORPORATION OF ILLINOIS.

SAVINGS BANK.

Application filed January 7, 1925. Serial No. 965.

Our invention relates to savings banks of the small portable type for holding coins and bills, and the general object of the invention is to provide a device of this character which is simply constructed and will readily admit the coins and bills and securely retain them after they have been inserted. Among the more specific objects it is my purpose to provide a cover which may be closed and locked by merely pressing it into its seat upon the body of the container. Another object is to provide a cover which is reversible end for end so that it may be locked onto the container in either position. Another object is to provide a latching plate which is slotted to receive the coins and which is held in latched position by springs which perform the additional function of retaining the coins after they are inserted. We obtain our objects by the construction illustrated in the accompanying drawings, in which

Figure 1 is a side elevation partly in section showing the complete device.

Figure 2 is a bottom plan view along the line 2—2 Figure 1.

Figure 3 is an end view taken partly in section on the line 3—3 Figure 1.

Figure 4 is a perspective view showing the under side of the cover, latching plate and associated parts.

Figure 5 is a perspective view showing the under side of the latching plate.

Like numerals denote like parts throughout the several views.

In the form selected to illustrate the invention the device includes a body 1 which forms the container. By preference it is elongated and is rabbeted at the upper inner margin to form a countersink 2 in which the cover may seat. The cover includes a cover plate 4 which seats in said countersink and is thereby prevented from shifting in the plane of the cover when the latter is seated. Said cover plate is provided with the usual coin slot 6.

A latching plate 8 shown separately in Figure 5 is slidably mounted on the under side of the cover plate, being held by lugs 10 here shown as being struck from the metal of the cover plate. Said latching

plate is cut away at the central portion for accommodating the tension springs and associate parts hereinafter mentioned.

The body 1 of the bank has two internal shoulders 12 oppositely located near the top of the body. At one end of the latching plate is a tongue 14 for passing under one of said shoulders, and at the other end is a bevelled projection or cam 16 for passing under the other shoulder for latching the cover in place. The purpose of the cam is to cause the latching plate to be repulsed temporarily as the cover is being pressed into place on the body.

The latch is normally urged into latching position by means of two helical tension springs 18, 19. These springs are fastened at one end to lugs 20 struck from the metal of the latching plate 8. They are fastened at the other end to lugs 22 struck from the metal of the cover plate 4. The result is that they constantly urge the latching plate in a direction to engage one of the shoulders 12 on the body.

It is desirable that the outline of the cover plate be symmetrical with the shoulders 12 at opposite ends of the body, thus making the cover reversible end for end.

The tension springs 18, 19 are arranged side by side adjacent to the coin slot 6. It is desirable that they be enclosed in tubular sections 27. These permit the springs to be flexed laterally to permit the coins to be inserted through the slot, and at the same time reduce the friction of the coins as they are being inserted. They have the further advantage of more completely closing the slot, for in practice they normally lie in tangential contact with each other or approximately so.

A keyhole slot 24 is formed in the cover plate adjacent to the latching cam 16. The latching plate has a corresponding slot 26 with the result that when a key is inserted and rotated it will retract the latching plate and cause the cam 16 to disengage the shoulder 12.

In practice, when it is desired to close the bank one end of the cover plate is first lowered into position on the body with the tongue 14 hooked under a shoulder 12. The

other end of the cover is then pressed downward, the shoulder 12 acting upon cam 16, repulsing the latching plate to permit the cam to clear the shoulder, whereupon the 5 latch plate will snap into locking position as shown in Figure 1. The cover cannot thereafter be removed except by the aid of a key. Thus it will be observed that to close and 10 lock the bank all that is necessary is to cause the tongue 14 to engage either of the shoulders 12 and thereafter press the locking plate into its seated position upon the body of the bank.

The construction is both simple and durable. The springs are made to perform the 15 dual function of urging the latching plate to acting position and to guard the coin slot to prevent the issue of coins out through it. Normally the coin slot will be entirely closed 20 and therefore there is no opportunity for thin coins to slip out. The device as a whole presents an attractive appearance, especially when the body is in the form of an elongated hexagon, as illustrated. The cover, 25 when in position is flush with the top of the body thus producing a smooth top and making it practically impossible to insert a prying tool between the cover and the body.

Having thus described our invention what 30 we claim as new and desire to secure by Letters Patent is:

1. A savings bank having a body, a cover 35 having a coin slot, a latch plate slidably mounted on the under side of the cover and long enough to simultaneously engage the body at diametrically opposite points to hold the cover locked in place, and springs connecting the cover and the latching plate for urging the latter toward locking position, said springs being arranged parallel 40 and adjacent to each other beneath the coin slots for preventing issue of the contents of the bank.

2. A savings bank having a body, a cover 45 having a coin slot, a latch plate slidably mounted on the under side of the cover and long enough to simultaneously engage the body at diametrically opposite points to hold the cover locked in place, springs connecting the cover and the latching plate for urging the latter toward locking position, said springs being arranged parallel and adjacent to each other beneath the coin slots for preventing issue of the contents of the 50 bank, and a set of short hollow cylinders encircling the springs and the cylinders on the two springs being normally held tan-

gential to each other by said springs, the latching plate being cut away at the central portion for permitting the cylinders to lie 60 closely adjacent to the under side of the cover.

3. A savings bank having a body which is internally rabbeted at the upper rim, said body being provided with two oppositely 65 located shoulders projecting inward near the top, a cover seating in the rabbeted rim of said body to prevent shifting in any direction when the cover is seated, a latching plate slidably mounted on the under side 70 of said cover and having a tongue at each end adapted to extend under the shoulders for holding the cover in place, one of the tongues sliding into and out of engagement with the adjacent shoulder for locking and 75 releasing the cover, and the other tongue maintaining a sliding engagement with the remaining shoulder when the cover is in place to thereby hold its portion of the 80 cover seated regardless of whether the opposite tongue is in engagement with its shoulder or not.

4. A savings bank having a body provided with an internal shoulder near the top, a cover seating on the body and having 85 a coin slot, a latch plate slidably mounted on said cover and being slidable into and out of engagement with said shoulder, and a pair of springs arranged alongside of and beneath said slot for retaining the contents 90 of the bank, one end of the springs being connected to the cover and the other end to the latch plate for urging the latter toward latching position.

5. A savings bank having a body provided with an internal shoulder near the top, a cover plate seating on the body and having a coin slot, a latch plate slidably mounted on the under side of the cover and movable into and out of engagement with 100 said shoulder, a pair of helical tension springs arranged alongside of and beneath said slot for preventing egress of the contents of the bank, one end of the spring being connected to the cover and the other end to the latch plate for urging the latter toward latching position, and tubular sections surrounding said springs for increasing 105 the coin retaining action thereof.

In witness whereof, we have hereunto 110 subscribed our names.

HENRY J. HALVERSON.

WILLIAM HAROLD YOUNGSTROM.
